UNITED STATES PATENT OFFICE.

JOHAN F. BJURLUND, OF RICHMOND HILL, NEW YORK, ASSIGNOR OF ONE-HALF TO
HENRY M. LASAUCHE, OF BROOKLYN, NEW YORK.

PACKAGE-FASTENER.

1,076,740.

Specification of Letters Patent.

Patented Oct. 28, 1913.

Application filed November 7, 1912. Serial No. 720,001.

To all whom it may concern:

Be it known that I, JOHAN F. BJURLUND, a citizen of the United States, and a resident of Richmond Hill, borough of Queens, 5 county of Queens, and State of New York, have invented a certain new and useful Improvement in Package-Fasteners, of which the following is a full, clear, and exact specification.

10 This invention relates to a class of devices adapted to be used for removably securing together a number of articles.

My invention has for its object primarily to provide a package fastener designed to 15 be utilized especially for facilitating the work of fastening and unfastening packages of letters, papers, or other articles so as to be conveniently carried by a person, or otherwise transported, and which is of a 20 form adapted to permit it to be used a great number of times, thereby dispensing with the use of cord, or like means as at present employed and saving the expense incidental thereto by reason of the cord being invariably severed and thrown away when the 25 package is unfastened. These advantages are mainly accomplished by providing two corresponding straps, and upon the ends of said straps is a clasp composed of two members 30 having interfitting tubular parts adapted to be quickly sprung into locked engagement by a catch of a form which permit the members to be easily separated when desired without impairing the usefulness of the 35 device.

A further object of the invention is to provide a package fastener of simple and efficient construction, and which may be made in various shapes and sizes.

40 With these and other objects in view, the invention will be hereinafter more particularly described with reference to the accompanying drawing, which forms a part of this specification, and will then be pointed 45 out in the claims at the end of the description.

In the drawing, Figure 1 is a perspective view of a package of papers with one form of fastener embodying my invention applied 50 theron. Fig. 2 is a top plan of the fastener. Fig. 3 is a side elevation of the fastener, and Fig. 4 is an enlarged view, partly broken away, of the male member of the fastener.

The device, or package fastener has preferably two flexible straps 10 and 11, though one, or any desired number of straps may be used, and said straps may be made of canvas, leather, or any other preferred material. The straps 10 and 11 are spaced apart in parallel relation, and the central parts thereof are connected by a transverse strap, as 12, which may be utilized as a handle, if desired. The ends of the straps 10 and 11 are adapted to be detachably connected by a clasp, as 13, which is preferably made of metal, and may be constructed in any suitable size as occasion requires.

The clasp 13 is composed of a male member 14 and a female member 15. The male member 14 has a substantially T-shaped body portion, or plate 16 whereby an arm 17 and two aligned transverse arms, as 18 and 19, are provided. In proximity to the free ends of the arms 18 and 19 are slots 20 and 21. One end of the strap 10 is secured in the slot 20 of the arm 18, and one end of the strap 11 is likewise secured in the slot 21 of the arm 19. The arm 17 is formed so that it is longitudinally curved, and a part of said arm is bent over so as to provide a tubular portion 22 which has an elongated slot, as 23 therein. At the end of the tubular portion 22 adjacent to the arm 18 is a lug 24, and in proximity to the opposite end of said tubular portion are aligned openings in which is rigidly held a pin 25 which is disposed crosswise with respect to the elongated slot 23. In the tubular portion 22 is a spring catch 26. The spring catch 26 is preferably made of wire of a well known form having one part thereof wrapped spirally around the pin 25, and disposed so that one of its ends rests against the inner surface of the tubular portion. As illustrated, the central part of the catch is bent laterally in approximately an L-shape to provide a retaining seat, as at 27, and this L-shaped seat is disposed through the elongated slot 23 and extends some distance beyond the exterior of the tubular portion 22. The part of the catch 26 opposite to its pivoted end is guided through the other end of the tubular portion, and terminates with a ring 28 in alignment with the lug 24. Obviously by this arrangement the spring catch 26 is tensioned so as to normally serve to force the L-shaped

retaining seat 27 outwardly of the slot 23 of the tubular portion 22. The female member 15 also has a substantially T-shaped body portion, or plate 29 whereby an arm 30 and two alined transverse arms 31 and 32 are provided. Adjacent to the free ends of the arms 31 and 32 are slots 33 and 33^a, respectively. The opposite end of the strap 10 is secured in the slot 33 and the corresponding end of the strap 11 is similarly secured in the slot 33^a. The arm 30, like the arm 17 of the female member, is formed so that it is longitudinally curved, and a part of said arm is bent over so as to provide a tubular portion 34 which is of sufficient diameter to permit the tubular portion 22 of the male member to be freely inserted therein. Through diametrically opposite parts of the tubular portion 34 are elongated slots 35 and 36 one of which is adapted to be registered with the slot 23 of the tubular portion 22 so as to receive the seat 27 of the catch 26 for holding in locked engagement the male and female members when interfitted together.

When the device is employed for fastening a number of letters, papers, or other articles together the straps 10 and 11 are guided around the package. The tubular portion 22 of the male member 14 is then passed into the tubular portion 34 of the female member 15 so that the seat 27 of the catch 26 will be disposed through one of the slots of said female member. The male and female members will thereby be locked together, and to release the members the ring 28 is forced toward the lug 24 against the tension of the catch 26. The retaining seat 27 of the catch 26 will thereby be directed inwardly of the tubular portions of the members, and the male member may readily be withdrawn from the female member.

In order to permit a package when secured by the device to be conveniently carried, upon the male member 14 at the juncture of its arms 17, 18, 19 is provided a short tube, or ring 37, and a similar tube, or ring 38 is provided upon the female member 15 at its juncture with the arms 30, 31, 32. By the use of a cord passed through the rings 37 and 38, or by connecting a handle of a suitable form thereto the package may then be carried in this manner, if desired.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described, my invention, I claim as new and desire to secure by Letters Patent:—

1. A device of the character described, comprising a member having a substantially T-shaped plate, the alined arms of which are connected to an object to be secured, a tubular portion formed at the free end of the third arm of the T-shaped plate, said tubular portion having a slot therethrough, a spring catch provided in the tubular portion and having a retaining seat projecting through the slot thereof, a second member having a substantially T-shaped plate, the alined arms of which are connected to an object to be secured, a tubular portion formed at the free end of the third arm of the T-shaped plate, said tubular portion being of a diameter whereby it may freely receive the tubular portion of the first member when inserted therein, and said tubular portion of the second member having a slot adapted to be registered with the slot of the tubular portion of the first member, whereby the retaining seat of the spring catch may be guided therethrough for holding the members in locked engagement when in mating arrangement.

2. A device of the character described, comprising a member having a substantially T-shaped plate, the alined arms of which are connected to an object to be secured, a tubular portion formed at the free end of the third arm of the T-shaped plate, said tubular portion having a slot therethrough, spring actuated means provided in the tubular portion and having a part thereof projecting through the slot, a second member having a substantially T-shaped plate, the alined arms of which are connected to an object to be secured, a tubular portion formed at the free end of the third arm of the T-shaped plate, said tubular portion being of a diameter whereby it may freely receive the tubular portion of the first member when inserted therein, and said tubular portion of the second member having a slot adapted to be registered with the slot of the tubular portion of the first member, whereby the projecting part of the spring actuating means may be guided therethrough for holding the members in locked engagement when in mating arrangement.

3. A device of the character described, comprising a member having a plate, an arm formed thereon and having a tubular portion formed upon its free end, said tubular portion having a slot therethrough, a spring wire having one end pivotally held in the tubular portion, and having a substantially L-shaped retaining seat projecting through the slot thereof, a ring formed upon the opposite end of the wire, a second member having a plate, an arm formed thereon and having a tubular portion formed on its free end,

said tubular portion being of a diameter whereby it may freely receive the tubular portion of the first member when inserted therein, and said tubular portion of the second member having a slot adapted to be registered with the slot of the tubular portion of the first member, whereby the L-shaped retaining seat of the spring wire may be guided therethrough for holding the members in locked engagement when in mating arrangement.

4. In a fastener, the combination of two mating members, said members being in the form of cylindrical tubes having open ends, and of such size that one will telescopically engage the other, a spring catch having a projecting shoulder disposed through a suitable slot provided in the side wall of the inner member, said catch being secured in the desired position by a vertically disposed pin and having a projecting arm at the rear end whereby the catch may be released, said outer member having a suitable opening provided in the wall thereof adapted for engagement with said catch, whereby the device may be secured in position as required to secure a package.

5. In a package fastener, the combination of two telescopically mating cylindrical members having open ends, each being suitably mounted on a plate, said plates being adapted to be secured to the package, the inner member of said fastener having a slot in one side thereof, a pin vertically disposed through the walls of said member and through an eye provided in a catch, said catch comprising a wire having its ends reflexively disposed within the said member, and having a projecting shoulder on one end extending through said slot and having an extended arm projecting beyond the end of said cylindrical member whereby the catch may be released, said outer member having an aperture in one side adapted for engagement with said shoulder of the catch whereby the fasteners may be secured in position as required for holding a package.

This specification signed and witnessed this sixth day of November A. D. 1912.
